UNITED STATES PATENT OFFICE.

FREDERICK GELSTHARP, OF TARENTUM, PENNSYLVANIA, ASSIGNOR TO PITTSBURGH PLATE GLASS COMPANY, A CORPORATION OF PENNSYLVANIA.

POLISHING RUNNER.

Application filed June 16, 1923, Serial No. 645,857. Renewed October 16, 1925.

To all whom it may concern:

Be it known that I, FREDERICK GELSTHARP, a citizen of the United States, and a resident of Tarentum, in the county of Allegheny and State of Pennsylvania, have made a new and useful Invention in Polishing Runners, of which the following is a specification.

The invention relates to the blocks or runners employed in polishing plate glass and involves an improvement over the construction of my application, Serial Number 601,089. It has for its principal objects the provision of improved means for attaching the felts to the metal runner block, whereby the assembly of blocks and felts is rendered more convenient, the labor incident to refelting is reduced, and the requirement of removing the runner blocks from the machine in order to refelt them is avoided. Certain embodiments of the invention are illustrated in the accompanying drawings wherein:

Figure 1 is a vertical section through a polishing runner embodying the invention. Fig. 2 is a bottom plan view of the device of Fig. 1. And Fig. 3 is a bottom plan view of a modified form of runner.

Referring to Figs. 1 and 2, 1 is a metal supporting block or plate; 2 is the framework from which the block is supported over the polishing table; 3 is the spindle by means of which the block or plate is mounted for universal movement in order to adjust itself to the surface of the glass over which the block is moved; 4 are securing or holding clips or plates; and 5 is the polishing pad or felt which is secured at its corners to the clips 4.

The lower end of the spindle 3 is provided with a ball 6 held in position by means of the clamp 7, which in turn is secured by the bolts 8, this being a common method of securing a polishing block to its spindle and permitting the necessary movement so that the block may adjust itself to the glass. The spindle 3 is held against withdrawal from the frame 2, when the table beneath the runners is removed, by means of the cotter pin 9.

The block 1 is preferably square as is also the felt sheet 5, but this is not necessarily the case as some other angular shape might be employed. The block and felt do not need to correspond in shape and size, al-

though this is preferably the case, all that is necessary being that the area of the member 1 be sufficient to give support to the entire upper surface of the felt or pad 5. The felt 5 is secured to the corner clips 4 by means of the cement 10, which for the purpose of illustration is shown as a relatively thick layer. The clips are preferably of triangular shape as indicated in Fig. 2 and are provided with upwardly extending shanks 11 upon which are threaded the clamping nuts 12.

The method of fastening the felt 5 to the block 1 as above described insures sufficient security and the felt assumes a perfectly flat position and wears uniformly throughout its area. As pointed out in my copending application heretofore referred to, the polishing effect of the square felt is more rapid than with the ordinary type of polishing block of circular shape, but having the same rubbing area.

The use of the clips 4 provides a convenient method of assembling and disassembling the blocks and felts. The clips can be made relatively thin and cheap, and little loss is involved in throwing them away with the worn felt, in case it is not found to be worth while to detach them for reuse. The arrangement makes it easy and convenient to detach a felt and replace it by another one without removing the runner from its supporting frame 2, the felts 10 being kept in stock with the clips cemented thereto ready for use. The clips, are as illustrated, seated in recesses in the lower face of the polishing block so that the lower face of the felt is not pressed downward at the corners, but lies in a perfectly true plane.

Fig. 3 illustrates the invention as applied to a circular polishing block 13, the felt 14 being in this instance cemented to the annular securing member 15 which corresponds in function to the clips 4 of the Fig. 1 construction. The annular member is held in place by means of upstanding shanks 16 which project through the metal block 13 and are held by nuts as in the construction of Fig. 1.

What I claim is:

1. In combination, a plate glass polishing runner comprising a supporting block, a sheet of polishing felt on the lower face of the block, and means for securing the felt to the block consisting of means cemented

to the upper surface of the felt sheet at the edge thereof and provided with holding members extending upwardly through the block, and releasable securing means for the upper ends of said members.

2. In combination, a plate glass polishing runner comprising a supporting block, recessed on the lower face at the edge thereof, a sheet of polishing felt on the lower face of the block, and means for securing the felt to the block consisting of means cemented to the upper surface of the felt sheet and adapted to fit into the recessed lower face of the block and provided with holding members extending upwardly through the block, and releasable securing means for the upper ends of said members.

3. In combination, a plate glass polishing runner comprising an angular sheet of felt,

holding clips cemented to the upper surface 20 of the sheet at the corners thereof provided with upwardly extending holding members, a supporting block perforated to receive the holding members, and clamping means for the upper ends of said members. 25

4. In combination, a plate glass polishing runner comprising an angular sheet of felt, holding clips cemented to the upper surface of the sheet at the corners thereof provided with upwardly extending threaded shanks, 30 a supporting block recessed to receive said clips and provided with perforations for said shanks, and securing nuts for said shanks.

In testimony whereof, I have hereunto 35 subscribed my name this 9th day of June, 1923.

FREDERICK GELSTHARP.
